Inventor
By his Attorney
J. Maccoemillward.

UNITED STATES PATENT OFFICE.

JOEL D. BARBER, OF TUCKAHOE, NEW YORK.

DESIGN FOR A GARMENT-RACK.

52,777.

Specification for Design.

Patented Dec. 24, 1918.

Application filed July 8, 1918. Serial No. 243,967. Term of patent 3½ years.

To all whom it may concern:

Be it known that I, JOEL D. BARBER, a citizen of the United States, residing in Tuckahoe, Westchester county, State of New York, have invented a new, original, and ornamental Design for a Garment-Rack, of which the following is a specification, reference being had to the accompanying drawing, forming a part thereof.

The figure is a perspective view of a garment rack embodying my invention.

I claim:

The ornamental design for a garment rack as shown.

JOEL D. BARBER.
